UNITED STATES PATENT OFFICE.

EDWARD A. EUSTICE, OF NEWTON, IOWA.

WRINGER-SUPPORT.

1,053,371.

Specification of Letters Patent. Patented Feb. 18, 1913.

Application filed June 1, 1911. Serial No. 630,697.

To all whom it may concern:

Be it known that I, EDWARD A. EUSTICE, a citizen of the United States, residing in Newton, county of Jasper, and State of Iowa, have invented a new and useful Improvement in Wringer-Supports, of which the following is a specification.

The object of my invention is to provide an attachment for a wringer support which may be so adjusted as to run the water taken from the clothes in either direction desired, and is particularly adapted for use with a reversible wringer for returning the rinsing water to the rinsing tub.

The wringer support and wringer which I employ are of the ordinary type, no particular style or construction being necessary, as my attachment may easily be secured to any standard construction.

My invention consists of certain details of construction, hereinafter set forth, pointed out in my claims, and illustrated in the accompanying drawings, in which—

Figure I shows a vertical sectional view of a wringer and wringer support and my attachment secured thereto, the dotted lines indicating the elevated position which the rear section of the attachment is designed to assume when desired; Fig. II shows a like view except that the forward section of my attachment is shown in an elevated position; and Fig. III shows a perspective view of a wringer support fitted out with my attachment.

Referring to the accompanying drawings the reference numeral 10 is used to indicate a portion of a washing machine to which a wringer support 11, may be either permanently or removably attached, said wringer and wringer support being of any desired standard type. The cross piece 12 of the wringer support, to which the wringer is designed to be secured, is, preferably, constructed of a strip of material provided with upwardly projecting end lugs, 13 and 14 respectively, each of which has a vertical inner face 15 and 16 respectively.

My attachment is constructed of two sections 17 and 18, preferably sheet metal, hinged together, as shown at 19, the forward section being of greater length than the rear section. Each of these sections is provided with upturned sides, as shown, and the forward section is pivotally secured to the cross piece 12, by means of pins, or the like, passing through orifices in their re-

spective upturned sides and being journaled in their respective lugs 13 and 14.

From the foregoing description it is apparent that each section is mounted for pivotal movement, the forward section from its bearings in the cross piece and the rear section from its hinged connections with the forward section. The downward limit of movement of section 18 is determined by the base of the wringer support.

Fingers 20 are pivoted to the cross-piece 12 and when in the position shown in Fig. 2 hold section 17 in raised position. A pin 21 is secured to lug 14 and projects beyond the inner end of the latter to engage the adjacent side of the section 17 to limit the downward movement of the section as depicted in Fig. 3 of the drawings.

My device is particularly adapted for use with a reversible wringer. When the two sections are each in their normal positions, reclining downwardly, the water wrung from the clothes will be received by the rear section and returned to the washing machine. When the wringer is reversed in operation, and clothes are being taken from a rinsing tub, the rear section is elevated and the water discharged from the clothes is received on the rear section and runs forwardly on same onto, and over, the forward section and is returned to the rinsing tub.

When clothes are being taken from the washing machine the forward section of my device may, if desired, be elevated and serve as a means to receive the clothes after they are wrung, the water, obviously, being returned to the washing machine.

Having thus described my invention what I claim and desire to secure by Letters Patent of the United States is;

1. In combination, with a support, having spaced end lugs, a drip board composed of a pair of sections, one of the sections being arranged in the space between said end lugs and being pivoted thereto, the other section having its inner end extending beyond the inner end of the first named section and being hinged thereto, a pivoted finger carried by the support to engage the bottom of said first mentioned section to hold the latter in raised position, and a pin carried by the support to engage the inner end of the first mentioned section to limit the downward movement thereof.

2. In combination with a support, a drip-board composed of a pair of sections, one

of the sections being pivotally connected between its ends to the support, the other section having its inner end projecting over and beyond the inner end of the first named section, and being hinged between its ends to said first named section, the free end portion of the second named section being for engagement with the support to restrict its downward movement, and means to engage

the first named section so that same will be held with its inner end in overlapping relation to the inner end of the second named section.

EDWARD A. EUSTICE.
